(57) **CLAIM**

The ornamental design for a shoe with opaque and translucent heel regions, as shown and described.

DESCRIPTION

FIG. 1 is a first rear perspective view of a shoe with opaque and translucent heel regions showing my new design;

FIG. 2 is a rear view thereof; and,

FIG. 3 is a second rear perspective view thereof.

The broken lines immediately adjacent to the shaded area represent unclaimed boundaries of the design. The broken lines showing an insole member form no part of the claimed design. The broken lines showing the remainder of the shoe are for environmental purposes only and form no part of the claimed design. The stipple shading adjacent to the translucent region represents an opaque region and does not represent any particular color, material, or texture.
